UNITED STATES PATENT OFFICE

171,214

TEXTILE FABRIC OR THE LIKE FOR GRILLS OF TELEVISION AND RADIO CABINETS

John A. MacIntyre, Barrington, R. I., assignor to B & M Mills, Inc., a corporation of Rhode Island

Application July 18, 1952, Serial No. 20,665

Term of patent 3½ years

(Cl. D92—1)

To all whom it may concern:

Be it known that I, John A. MacIntyre, a citizen of the United States of America, residing at Barrington, county of Bristol, State of Rhode Island, have invented a new, original, and ornamental Design for a Textile Fabric or the Like for Grills of Television and Radio Cabinets, of which the following is a specification, reference being had to the accompanying drawing, forming a part thereof.

Figure 1 is a plan view of a textile fabric or the like for grills of television and radio cabinets showing my new design.

I claim:

The ornamental design for a textile fabric or the like for grills of television and radio cabinets, substantially as shown.

JOHN A. MACINTYRE.
